STILT

Charles E. Collins, Kansas City, Mo.

Application August 7, 1933, Serial No. 684,008

8 Claims. (Cl. 272—70.1)

My invention relates to improvements in stilts. It relates to a stilt of the type having a leg and a foot support for the operator vertically adjustable on said leg.

5 One of the objects of my invention is the provision of novel resilient means for supporting the leg of the stilt.

A further object of my invention is the provision of a novel support for the foot of the operator, and which can be easily and quickly vertically adjusted on the leg through the intermediary of the operator's foot while the stilt is in use.

Still another object of my invention is the provision of novel means for yieldingly holding the foot support from upward movement during the usual operation of the stilt in walking.

Another object of my invention is the provision of a stilt of the kind described, which is simple, cheap to make, easily operated, durable, not likely to get out of order, and which eliminates jar and is comfortable when operated.

The novel features of my invention are hereinafter fully described and claimed.

In the accompanying drawing which illustrates 25 my invention,

Fig. 1 is a side elevation, partly broken away, of my improved stilt.

Fig. 2 is another side elevation of the same 30 part of the leg being broken away.

Fig. 3 is an enlarged top view of the stilt, partly broken away.

Fig. 4 is an enlarged view, similar to Fig. 3, with other parts omitted and parts broken away.

35 Fig. 5 is an enlarged section on the line 5—5 of Fig. 3.

Fig. 6 is a reduced side elevation of a portion of the stilt, showing the foot support raised and released from gripping action on the leg.

40 Similar characters of reference designate similar parts in the different views.

1 designates a vertical, tubular portion preferably, of the leg of the stilt, the portion 1 having fastened to its lower end a block 2 having there-through a transverse slot in which is longitudinally slidably adjustable a horizontal resilient portion 3 of the foot of the stilt. Said foot is preferably formed of a strip of resilient metal, such as spring steel or spring brass having an arcuate portion 4, provided at its under side with an arcuate tread to which is fastened an exteriorly roughened strip of yielding material 5, preferably soft rubber, which holds the foot from slipping in the walking operation.

55 The portion 3 is held from movement from its

adjusted position by a set screw 6 fitted in a threaded hole in the under side of the block 2 and bearing against the portion 3. A lock nut 7 on the screw 6 bears against the block 2 and holds the screw from loosening.

Extending under and bearing against the portion 3 is an end portion 8 of the foot. This portion assists in supporting the portion 3. By springing the portions 3 and 8 apart, the block 2 may be applied to or removed from the portion 3. 5

For supporting the foot of the operator, there is provided a foot support comprising a plate having an inclined portion 9 having a hole 10 through which the leg portion 1 extends. Said plate at one side of the leg portion 1 has a horizontal portion 11 adapted to support the foot of the operator of the stilt. Said portion 11 has attached to its under side a U shaped spring the arms 12 of which have respectively on their inner sides concave seat portions 13 adapted to respectively releasably grip opposite sides of the leg portion 1 to hold the portion 11 from upward swinging in the 10 operation of walking.

For gripping the leg portion 1, there are provided two gripping members 14 and 15, which are respectively disposed at opposite sides of the leg portion 1, and each of which pivotally engages the inclined portion 9, the latter having at opposite sides of the hole 10, in which said members 14 and 15 are disposed, two pointed 15 projections 16 which respectively enter and are loosely fitted in recesses provided in the adjacent sides of the members 14 and 15, Fig. 3, said recesses being designated 17.

When downward pressure is exerted against the platen portion 11 by the operator's foot, the members 14 and 15 will grippingly engage the leg portion 1. The upwardly lifting of the plate portion 11 will release the leg portion 1 from the gripping action of the members 14 and 15, so 20 that the operator may raise or lower the foot support on the leg portion, as he may desire.

In order that the operator may lift the portion 11 for such adjustment, an arcuate strap is disposed above and has its ends fastened to the 25 portion 11, said strap being designated by 18. This strap is adapted to embrace the upper side of the operator's shoe, as shown in dotted lines in Fig. 1.

To normally hold the portion 11 from being 30 upwardly lifted during the operation of walking on the stilt, the spring U shaped member 12 is provided, as has been described.

By loosening the set screw 6, the leg may be 35 adjusted lengthwise of the horizontal portion 3,

which portion is disposed in a chord of the arc of the tread of the arcuate portion 4 of the foot of the stilt. By adjusting the leg from the middle toward one end of the portion 3, the resilient action is reduced, and the device is adapted for a heavier person.

When the operator, while walking desires to raise or lower the foot support, he will raise his foot against the strap 18 with sufficient pressure to swing upwardly the portion 11 against the holding effect of the U shaped spring 12. When this is effected, as shown in Fig. 6, the operator may with his foot raise or lower the foot support. Upon adjusting the foot support to the desired position, the operator presses downwardly on the portion 11, thus moving the latter downwardly so as to effect a gripping action of the members 14 and 15 upon the leg portion 1. This swinging downwardly of the portion 11 will again engage the spring 12 with the leg portion 1, as shown in Figs. 2, 4 and 5. The stilt may then be used in the usual manner for walking.

By pivoting the leg gripping members 14 and 15 to the portion 9 of the foot support, and providing the members with gripping surfaces of substantial area, said surfaces will lie flatwise against the leg, when downward pressure is exerted on the portion 11 of the foot support, thereby avoiding liability of the gripping members indenting or marring the leg, when the latter is clamped thereby.

I do not limit my invention to the structure shown and described, as many modifications, within the scope of the appended claims, may be made without departing from the spirit of my invention.

What I claim is:—

1. A stilt having a leg, a foot support movable upwardly and downwardly relative thereto, and two gripping members pivoted to said foot support and disposed respectively at opposite sides of said leg and having gripping surfaces of substantial area which lockingly grip said leg when said foot support is swung downwardly, and which are released from said leg when said foot support is swung upwardly relatively to said leg.

2. A stilt having a leg, a foot support movable upwardly and downwardly relatively thereto, two gripping members pivoted to said foot support and disposed respectively at opposite sides of said leg and having gripping surfaces of substantial area which lockingly grip said leg when said foot support is swung downwardly, and which are released therefrom when said foot support is swung upwardly, and means normally yieldingly holding said foot support in the gripping position.

3. A stilt having a leg, a foot support movable upwardly and downwardly relatively thereto, two gripping members pivoted to said foot support on horizontal axes and disposed respectively at opposite sides of and adapted to lockingly grip said leg when said foot support is swung downwardly, and releasable from said leg when the foot support is upwardly swung, and a spring fastened to said foot support and having means, when the latter is swung downwardly to the leg locking position to releasably embrace opposite sides of said leg for holding the foot support in the locking position, said spring being released from holding engagement with said leg upon a predetermined force being exerted upon said foot support tending to swing the latter upwardly.

4. A stilt having a leg, and provided with a foot having an arcuate tread portion and a horizontal portion extending from one end of said arcuate portion toward the other end thereof, said leg having its lower end portion adjustable lengthwise of and provided with means for being rigidly attached to said horizontal portion.

5. A stilt having a foot provided with an arcuate tread portion, and a resilient horizontal portion between the ends of said tread portion, and a leg having its lower end portion rigidly fastened to and supported by said resilient horizontal portion.

6. A stilt having a resilient bow shaped foot having resilient horizontal portions extending toward each other from the ends of the bow, one of said portions resting upon the other, and a leg adapted to support the weight of the user and having its lower end portion adjustable lengthwise of the upper one of said horizontal portions and having means for being rigidly fastened thereto in the position to which it is adjusted thereon.

7. A stilt having a foot comprising a strip of resilient material provided with an arcuate portion and a horizontal portion extending from one end of said arcuate portion toward the other end thereof, and a leg adapted to support the weight of the user and fastened rigidly to said horizontal portion.

8. A stilt having a foot comprising a strip of resilient material having an arcuate tread portion and a horizontal portion extending from one end of said arcuate portion toward the other end thereof, and a leg adapted to support the weight of the user and adjustable on and lengthwise of and having means for being rigidly fastened to said horizontal portion.

CHARLES E. COLLINS.
